CAGE CONSTRUCTION

Max L. Shulman, Washington, D. C.

Application August 20, 1937, Serial No. 160,174

3 Claims. (Cl. 119—17)

The invention relates to cage construction and more especially to bird cages.

The primary object of the invention is the provision of a cage of this character, wherein the 5 crown of its body carries a removable cap or head piece which is separable from without the body, so that access may be had to the interior of the body at the top thereof.

Another object of the invention is the provision of a cage of this character, wherein the removable cap or head piece carries a swinging perch which is readily extractable through the open top of the cage body and in this manner the former, as well as the perch can be conveniently and more thoroughly cleaned to have the cage sanitary.

A further object of the invention is the provision of a cage of this character, wherein the cap or head piece in its removable fitting with the 20 body of the said cage has associated therewith a gasket or washer of the resilient kind and such cap or head piece is releasably latched in position, being releasable from without the body of the cage.

A still further object of the invention is the provision of a cage of this character, which is extremely simple in construction, thoroughly reliable and efficient in operation, strong, durable, easily cleaned, and inexpensive to manufacture.

With these and other objects in view the invention consists in the features of construction, combination and arrangement of parts as will be hereinafter more fully described, illustrated in the accompanying drawing, which discloses the 35 preferred embodiment of the invention, and pointed out in the claims hereunto appended.

In the accompanying drawing:

Figure 1 is a vertical sectional view through a bird cage constructed in accordance with the invention.

Figure 2 is a fragmentary plan view looking toward the inner face of the crown portion with the cap or headpiece removed.

Figure 3 is an inner face view of the cap or headpiece removed from the body of the cage.

Similar reference characters indicate corresponding parts throughout the several views in the drawing.

Referring to the drawing in detail A designates 50 generally a portion of a bird cage which involves as usual a base or bottom plan 10, in this instance of circular shape, although it may be of any other shape, being preferably made from sheet metal stamped or otherwise dished.

In association with the base or bottom pan 10,

as is usual, is the body 11, in this instance being a wire frame having an arched or convex shaped crown portion 12. This arched or convex shaped crown portion at its center carries a keeper ring 13 forming an opening 14 in said portion. 5

The keeper ring 13 is provided in its inner periphery with diametrically opposed notches 15, the opening 14 being of the desired size for a purpose presently described.

Covering the opening 14 is a removable cap or 10 head-piece 16 overlapping for a distance the crown portion 12 and at the inner side of said cap or head-piece 16 is an inverted substantially T-shaped latch 17 which is passed through the notches 15 and on the turning of the cap or head- 15 piece 16 frictionally locks with the keeper ring 13, and in this manner the cap or head-piece is separably fastened in place on the body 11 at the crown portion 12 thereof for the closing of the opening 14 in the latter. 20

The ring 13 serves as a seat for a gasket or sealing washer 18 made from cork, rubber or a composition of materials which closes the joint between the said ring and cap or head-piece.

Centrally fitted in the cap or head-piece 16 is 25 a hanger 19 formed with an eye 20 without the cap or headpiece, while suspending within the body 11 a swing perch 21 which freely passes through the opening 14 and notches 15, respectively, when the cap or head-piece is detached, 30 so that said perch 21 and the latter can be readily and conveniently cleaned. The eye 20 is for the hanging of the cage or the carrying of the same in the hand. 35

From the foregoing it is thought that the construction and manner of operation of the invention will be clearly understood and therefore a more extended explanation has been omitted. It is to be understood that changes, variations and modifications may be made in the invention 40 as fall properly within the scope of the appended claims, without departing from the spirit of the invention or sacrificing any of its advantages.

What is claimed is:

1. A cage having a top, an opening in said top 45 and a perch holder and perch secured to said top at said opening; said opening having slots extending therefrom in opposite directions forming an opening of greater dimension than the first named opening whereby a perch having a 50 length greater than the first named opening and less than the second opening may pass through the opening and be removed from the cage.

2. The combination of a cage for flying birds, the cage having a top, the top having a central 55

- opening surrounded by a ring, a cap larger than the opening and having a depending generally cylindrical member capable of extending through the ring, and a perch supported by the cap, capable of passing through the ring and depending within the cage when the cap is on the cage, said ring and said cylindrical member having interlocking structure which when interlocked prevents vertical movement of the cage relative to the cap and perch, and which in another position permits the cap and perch to be removed as a unit from the cage, whereby the perch may be inserted and removed by a person without insert-

ing any part of the person's body or any tool into the cage.

3. The combination of a cage body, a cap therefor, said cage body having at its top a ring with a horizontal flange formed with slots, said cap having a closure adapted to pass through the ring and be supported therefrom, and a perch depending from the cap, said slots being of such extent as to permit passage of the perch through the slots when the closure is moved through the ring, 10 during removal of the cap from the cage. 5
